ATTORNEY

UNITED STATES PATENT OFFICE.

MARVIN W. SMITH, OF CANTON, SOUTH DAKOTA.

WELL POINT AND STRAINER.

1,236,615.

Specification of Letters Patent. Patented Aug. 14, 1917.

Application filed September 1, 1915. Serial No. 48,473.

To all whom it may concern:

Be it known that I, MARVIN W. SMITH, a citizen of the United States, residing at Canton, in the county of Lincoln and State 5 of South Dakota, have invented certain new and useful Improvements in Well Points and Strainers, of which the following is a specification.

My invention relates to the class of earth 10 boring and more particularly to a penetrating member and strainer for use in sinking wells and the like.

My invention has as its primary object the provision of a new and simple penetrating 15 tool having a perforated body, and a strainer in position therein and to prevent ingress of foreign materials.

Another object of my invention is to provide a device of the class above mentioned 20 having perforations therein which are formed in such a manner as to prevent clogging of the strainer.

With the above and other objects in view 25 my invention resides preferably in the construction, combination and arrangement of parts as hereinafter set forth in the specification and illustrated in the accompanying drawings, in which

Figure 1 is a longitudinal sectional view 30 of the penetrating tool embodying the improvements of my invention.

Fig. 2 is a similar view of the tubular outer casing.

Fig. 3 is a side elevation of the strainer.

Fig. 4 is a transverse sectional view taken 35 on the line 4-4 of Fig. 1, looking in the direction of the arrows, and

Fig. 5 is a side elevation of the penetrating member.

Similar reference characters designate 40 similar parts throughout the various views of the drawing.

In the drawing, wherein the preferred embodiment of my invention is illustrated, I 45 provide a tubular casing 1 having a threaded extremity 2 for the reception of a connecting nipple 3. The penetrating member comprises a square tapering block 4, having a circular flange 5 formed on the larger 50 extremity thereof. The tubular member 1 is connected with the penetrating element 4 by means of a transverse pin 6 having a threaded extremity for reception in openings 7 and 8 formed in the flange 5 and tubular 55 member 1 respectively. The tubular mem-

ber 1 is provided with a plurality of apertures 9, said apertures being diagonally disposed in the wall of the tubular member 1. It is essential that these openings be placed as shown in the drawing, that is, opening on 60 the outer surface tubular member 1, in such a manner as to prevent ingress of foreign matter while performing a boring operation.

The tubular housing or body 1 serves to protect a strainer 10 having a closing cap 11 65 at one extremity thereof and a retaining band 11' at the opposite extremity thereof. A strengthening band 12 may be disposed intermediate the length of the strainer 10 in order to strengthen the same and prevent 70 clogging. The band 11' may be soldered or otherwise secured to the screen 10. The end cap 11 is provided with a plurality of perforations through which connecting and strengthening loops 13 and 14 are adapted 75 to extend the free extremities of said loops being overlapped and adapted to receive the pin 6 as shown to advantage in Fig. 1. The bands surrounding the strainer 10 serve to maintain the same in spaced relation with 80 the inner surface of the tubular housing, permitting of a large area for the accommodation of liquid of any kind which is "struck" in the course of boring.

Attention is directed to the square tapered 85 penetrating member 4. I have found this to be the most advantageous form of penetrating head for use in connection with the housing provided. It will be noted that the peculiar disposition of the openings 9 obviates the clogging of the strainer without interfering with the ingress of liquid. It will be noted that the cap 11 abuts the flange 5 and thereby prevents wobbling of the 90 strainer.

While I have shown and described my invention as possessing a peculiar form and construction, it is desired that it be understood that I may make such changes in the details thereof that do not depart from the 100 spirit and scope of the invention as claimed.

Having thus described my invention, what I claim and desire to secure by Letters Patent is:

1. A device as specified, including a tubular perforated body, a penetrating head on one extremity of said body, connecting means for said head and body, a strainer in said housing, spacing bands associated with said strainer, an end cap therefor, and loops 105 110

carried by said strainer adapted for connection with the head and body to prevent displacement of said strainer.

2. A well point including a penetrating head, a tubular body mounted on the penetrating head, said body having obliquely disposed apertures, a stud for securing the body to the head, a screen within the body, a spacing head at one end spacing rings between the screen and the tubular body and

connecting loops arranged to be secured to the stud for retaining the screen in position.

In testimony whereof I affix my signature in presence of two witnesses.

MARVIN W. SMITH.
